HUNTING KNIFE

John F. McLean, Goderich, Ontario, Canada

Application July 11, 1950, Serial No. 11,071

Term of patent 14 years

(Cl. D22—3)

To all whom it may concern:

Be it known that I, John F. McLean, a citizen of Canada, residing at Goderich, in the county of Huron, Province of Ontario, Canada, have invented a new, original, and ornamental Design for Hunting Knife, of which the following is a specification, reference being had to the accompanying drawing, forming part thereof, in which:

Fig. 1 is an end elevation of the hunting knife as viewed from the tip of the blade,

Fig. 2 is a side elevation of the hunting knife,

Fig. 3 is a plan view of the hunting knife as viewed from the back, and

Fig. 4 is an end elevation of the hunting knife as viewed from the end of the handle remote from the blade.

I claim:

The ornamental design for a hunting knife, as shown.

JOHN F. McLEAN.
